UNITED STATES PATENT OFFICE.

ROBERT P. CARR, OF BUFFALO, NEW YORK, ASSIGNOR TO U. S. HAME COMPANY, OF BUFFALO, NEW YORK.

TRACE CONNECTER FOR HAMES.

Application filed October 3, 1924. Serial No. 741,342.

To all whom it may concern:

Be it known that I, ROBERT P. CARR, a citizen of the United States, residing at Buffalo, in the county of Erie and State of New York, have invented a new and useful Improvement in Trace Connecters for Hames, of which the following is a specification.

This invention relates to improvements in trace or draft connecters of the kind which are commonly referred to as ratchets and which are attached to hames and are provided with a series of holes or openings in any of which the usual trace hooks are adapted to engage to vary the elevation at which the draft is applied to the hames.

Heretofore these trace connecters have been made of malleable iron and in view of the fact that these devices when in use are subjected to severe strain, it has not been practical to make them of stamped or drawn metal.

The objects of this invention are to provide a trace connecter or hame ratchet which is so constructed that the same can be made of stamped or drawn sheet metal; also to improve the construction of devices of this kind in other respects hereinafter specified.

In the accompanying drawings:

Fig. 1 is a face view of a metal blank from which a trace connecter embodying my invention is made.

Fig. 2 is a face view of the completed trace connecter.

Fig. 3 is a side elevation thereof.

Fig. 4 is a front view of a hame provided with a trace connecter embodying the invention.

Figs. 5 and 6 are transverse sectional elevations thereof on line 5—5 and 6—6 respectively.

Fig. 7 is a fragmentary longitudinal sectional elevation thereof on line 7—7, Fig. 2.

Referring to Fig. 4, A represents a hame which may be of any usual or suitable construction and having the usual rein ring a secured to the upper portion thereof and the hame loop a' at the lower end thereof.

B represents the trace connecter or "ratchet", as it is commonly called, which is rigidly secured to the hame and is provided with a plurality of holes into which a trace hook b is adapted to enter, the holes being provided to permit the draft strains from the tug or trace to be applied to that portion of the hame which best suits the particular animal on which the hame is used. The trace connecter or ratchet also supports a breast strap ring b' at the lower portion thereof.

My improved trace connecter, as best shown in Figs. 2 and 3 includes two substantially flat end portions 10 and 11 which are provided with any suitable means for securing the connecter to a hame, such as the usual holes through which rivets or bolts are adapted to pass, the ends of the connecter being connected by a longitudinal bridge portion or rib 12, from which side flanges 13 and 14 extend laterally. The outer edges of the flanges extend into substantially the same plane as the end portions 10 and 11 and are adapted to contact or lie against a side of a hame and each of the flanges is provided with a series of holes 15, one hole of each flange being disposed oppositely to a hole in the opposite flange and adjacent holes are preferably spaced apart at equal distances so that the two hooked portions b², Fig. 4, usually provided on trace hooks b may be passed through adjacent pairs of holes 15 to permit the trace hook to grip the bridge portion or rib 12 of the trace connecter. The flanges 13 and 14 are preferably also provided with the usual holes 16 formed in recessed portions 17 of the flanges through which additional rivets or fastening devices may pass for securing the trace connecter to a hame.

The bridge portion or rib 12 of the trace connecter is made arch-shaped or of substantially inverted U-shaped cross section as is clearly shown in Figs. 5 and 6 and near the opposite ends of the trace connecter the bridge portion is bent or inclined as indicated at 17 and 18, the bent portions

terminating in the end portions 10 and 11 respectively of the trace connector. The inclined bent portions 17 and 18 of the bridge member or rib are also of channel-shaped cross section so that the entire rib or bridge member is of rigid construction and is well adapted to resist the strain to which the trace connector is subjected in use.

The portions of the metal surrounding 10 the holes 15 adjacent to the bridge portion of the trace connector are preferably bent inwardly toward each other as shown at 20, and this is preferably done without rupturing the metal adjacent to the holes 15. By 15 means of this formation of the metal at the upper portion of the holes 15, the hooked portions of the trace hooks *b* may be readily inserted through adjacent pairs of holes to grip or engage the rib portion 20 of the trace connector, and by means of this construction the strength of the rib member is not impaired as it would be if the holes were cut out to a greater extent to accommodate the trace hooks.

25 In the manufacture of the trace connector the metal from which the connector is made is first stamped out in the form of a flat blank as shown in Fig. 1, after which the flat blanks are placed into a die and pressed 30 into the form shown in Figs. 2 and 3. The blank shown in Fig. 1 is provided near one end with recesses 21 in the opposite sides thereof, which when the trace connector is bent into the desired shape, forms a recess 35 22 which is adapted to receive the breast strap ring *b'*. At the other end of the blank shown in Fig. 1 a pair of indentations or recesses 24 is formed, one of these recesses being formed at each side of the blank, 40 which, when the trace connector is completed, form the recesses 25 therein. The recesses 21 and 24 in the blank are quite essential to the successful manufacture of these trace connectors for the reason that 45 in forming the blank into a finished trace connector, the inclined portions 17 and 18 at the opposite ends of the bridge portion or rib of the trace connector are bent toward the ends of the flanges 13 and 14, so 50 that the recesses are considerably reduced in size during the forming process, as will be evident in comparing Figs. 1 and 2. Consequently it would be extremely difficult if not impossible to form the connector by 55 means of a die, unless recesses were provided between the opposite flanged portions 13 and 14 of the trace connector and the end portions 10 and 11 thereof, since otherwise the portions of the flanges adjacent to the opposite ends of the trace connector would 60 have to be deformed or buckled, and this would cause breaking of dies, as well as weakening the trace connector near the ends thereof. By making the opposite inclined 65 end of the bridge portion or rib of the trace

connector of substantially U-shaped cross section, the strength of the trace connector is not in any way impaired by the recesses or depressions 22 and 25 therein.

I claim as my invention:

1. A trace connector made of a single piece of sheet metal bent to form a substantially central longitudinally extending rib of arch-shaped cross section and flanges extending laterally from said rib and provided with oppositely arranged holes through which a trace hook may be inserted. 70

2. A trace connector made of a single piece of sheet metal bent to form a substantially central longitudinally extending rib of arch-shaped cross section and flanges extending laterally from said rib and provided with oppositely arranged holes through which a trace hook may be inserted, said rib terminating in end portions adapted to be secured to a hame. 75

80 3. A trace connector made of a single piece of sheet metal bent to form a substantially central longitudinally extending rib of arch-shaped cross section and flanges extending laterally from said rib and provided with oppositely arranged holes through which a trace hook may be inserted, said rib having oppositely inclined portions which are 85 also of arch shaped cross section and which terminate in end portions adapted to be secured to a hame. 90

95 4. A trace connector made from a single flat piece of sheet metal and bent into substantially trough shape, said connector including a central rib portion extending longitudinally thereof and which is of channel shaped cross section and from which flanges extend laterally in opposite directions and at an inclination from said rib 100 portion, said flanges being provided with holes into which a trace hook may be inserted, and recesses at opposite ends of said flanges which extend laterally from the edges of said trace connector toward the rib 105 thereof. 110

115 5. A trace connector made from a single flat piece of sheet metal and bent into substantially trough shape, said connector including a central rib portion extending longitudinally thereof and which is of channel shaped cross section and from which flanges extend laterally in opposite directions and at an inclination from said rib 120 portion, said flanges being provided with holes into which a trace hook may be inserted, and recesses at opposite ends of said flanges which extend laterally from the edges of said trace connector toward the rib thereof, said rib having oppositely inclined end portions adjacent to said recesses, said end portions being bent in a direction to partially close said recesses. 125

130 6. A trace connector made from a single flat piece of sheet metal and bent into sub-

stantially trough shape, said connector including a central rib portion extending longitudinally thereof and which is of channel shaped cross section and from which flanges extend laterally in opposite directions and at an inclination from said rib portion, said flanges being provided with

holes into which a trace hook may be inserted, said holes terminating in proximity to said rib portion and the metal about the holes adjacent to said rib portion being bent inwardly to facilitate the insertion of a trace hook.

ROBERT P. CARR.
